(57) **CLAIM**

The ornamental design for a “wireless communication adapter for game machine”, as shown and described.

DESCRIPTION

FIG. 1 is a front elevational view of my new design for a wireless communication adapter for game machine;

FIG. 2 is a top plan view thereof;

FIG. 3 is a rear elevational view thereof;

FIG. 4 is a bottom plan view thereof; and,

FIG. 5 is a right side view thereof, the left side view being a mirror image thereof.
